UNITED STATES PATENT OFFICE

2,485,388

SKIRT HANGER

George A. Kuhn, Chicago, Ill.

Application November 17, 1947, Serial No. 786,431

4 Claims. (Cl. 211—89)

1

This invention appertains to new and useful improvements in devices adapted to be utilized in association with retaining clothing and the like in a neat, convenient arrangement.

An object of this invention is to provide resilient means for locking skirts, trousers, and other articles of clothing in a neat and convenient arrangement.

Another object of this invention is to provide resiliently urged means having latching means associated therewith for retaining a pair of plates in juxtaposition.

Another object of this invention is to provide an improved resilient strap having spaced apertures therein at predetermined spacing, the apertures being used for the purpose of extending a support including a pair of rods through the apertures.

Another purpose of this invention is to provide means for limiting the travel of the resilient straps on the said support.

Another purpose of this invention is to provide an extremely simple device of the character described which lends itself well to commercial manufacture.

Ancillary objects and features of novelty will become apparent to those skilled in the art, and following the description of the preferred form of the invention, illustrated in the accompanying drawings, wherein:

Figure 1 is an elevational side view of the preferred form of the invention;

Figure 2 is a plan view of the invention shown in Figure 1;

Figure 3 is a sectional view taken substantially on the line 3—3 of Figure 1 and in the direction of the arrows; and

Figure 4 is an enlarged sectional detail of construction illustrating the latch means associated with the straps and forming a portion of the present invention.

This invention has been developed to provide a device for hanging articles of clothing in a convenient, space-saving manner.

A support is provided which is composed of a pair of spaced rods 10 and 12, respectively, having an end plate 14 secured thereto. This end plate has a plurality of apertures therein adapted to receive any suitable attaching means, such as screws, bolts or the like. Of course, the attaching means may then be fixed to a wall, door or other suitable member.

A connecting member 16 is associated with the said rods 10 and 12, respectively, and is angularly inclined relative to the longitudinal axis thereof.

2

A plurality of protuberances 18 are supplied on the said rods 10 and 12, respectively, for a purpose to be described hereinafter.

Means for resiliently retaining a pair of trousers, a skirt or a similar article of clothing 20 is provided. This means is composed of a resilient strap 22, preferably of a suitable metal, which has two sets of apertures therein. The first set of apertures is spaced substantially a distance equal to the distance between the rods 10 and 12. Of course, the said rods project through this first set of apertures. A second set of apertures is provided adjacent the other end of the strap 22 and this set of apertures is spaced a distance greater than the distance between the rods 10 and 12. This last-mentioned set of apertures is also used in association with the rods.

As is seen by inspection of Figure 3, the ends of the said resilient straps 22 are provided with a pair of plates 24 and 26, respectively, which are adapted to receive the article of clothing 20 therebetween.

The principle of locking the trousers, skirts or the like in or between the plates 24 and 26 is accomplished by the spring sliding on the lower rod 12. This spring or strap will bulge as it is slid due to the fact that the said second set of apertures is spaced a distance greater than the distance between the rods 10 and 12. This operation causes a tension on the lower rod, locking the plates in a closed position.

All that is necessary to release the article of clothing is to press the bulge in the strap or spring 22, thereby snapping the same to an open position. The limit of travel of the straps 22 is obviously defined by the protuberances 18 and by the connecting member 16. By this construction the general arrangement of straps 22 is retained.

It is apparent that variations may be made from the structure of the preferred embodiment of the invention without departing from the spirit of the inventive concept.

Having described the invention, what is claimed as new is:

- 45 1. In a hanger for clothing, a support including a first and a second rod in vertically spaced relation, means for retaining articles of clothing including a resilient strap having a first pair of apertures spaced a distance equal to the distance between said rods, and a second pair of apertures in said strap spaced a distance greater than the distance between said rods, thereby effecting a frictional lock on one of the rods for said strap.
- 50 2. In a hanger for clothing, a support including a first and a second rod in vertically spaced

relation, means for retaining articles of clothing including a resilient strap having a first pair of apertures spaced a distance equal to the distance between said rods, a second pair of apertures in said strap spaced a distance greater than the distance between said rods, thereby effecting a frictional lock on one of said rods for said strap, and a plate secured to each free end of said strap for holding engagement with an article of clothing.

3. In a hanger for clothing, a support including a first and a second rod in vertically spaced relation, means for retaining articles of clothing including a resilient strap having a first pair of apertures spaced a distance equal to the distance between said rods, a second pair of apertures in said strap spaced a distance greater than the distance between said rods, thereby effecting a frictional lock with one of the rods for said strap, a plate secured to each free end of said strap for engagement with an article of clothing, and a bar connected to the outer end of each rod and inclined relative to the longitudinal axes thereof for limiting the travel of said strap.

4. In a hanger for clothing, a support including a first and a second rod in vertically spaced relation, means for retaining articles of clothing including a resilient strap having a first pair of apertures spaced a distance equal to the distance between said rods, a second pair of apertures in said strap spaced a distance greater than the distance between said rods, thereby effecting a frictional lock with one of the rods for said strap, a plate secured to each free end of said strap for holding engagement with an article of clothing, and means associated with said rods for limiting the travel of said strap.

20 4. In a hanger for clothing, a support including a first and a second rod in vertically spaced relation, means for retaining articles of clothing

including a resilient strap having a first pair of apertures spaced a distance equal to the distance between said rods, a second pair of apertures in said strap spaced a distance greater than the distance between said rods, thereby effecting a frictional lock with one of the rods for said strap, a plate secured to each free end of said strap for engagement with an article of clothing, and a bar connected to the outer end of each rod and inclined relative to the longitudinal axes thereof for limiting the travel of said strap.

10 5. GEORGE A. KUHN.
